UNITED STATES PATENT OFFICE.

PETER J. WESTPHAL, OF HOLYOKE, MASSACHUSETTS.

THREAD-WINDING MACHINE.

SPECIFICATION forming part of Letters Patent No. 693,196, dated February 11, 1902.

Application filed March 6, 1901. Serial No. 50,063. (No model.)

To all whom it may concern:

Be it known that I, PETER J. WESTPHAL, a citizen of the United States of America, residing at Holyoke, in the county of Hampden and 5 State of Massachusetts, have invented new and useful Improvements in Thread-Winding Machines, of which the following is a specification.

This invention relates to improvements in 10 thread-winding machines, and has especial reference to the improvement of devices for regulating the pressure which the cops are subjected to by the thread-guide and to means for varying the tension placed upon the 15 thread as it passes onto the cop, whereby said tension may be changed or regulated in proportion to the change in the diameter of the cops.

A further object of the invention lies in 20 the adaptation of a stop-motion operated by the movement of the thread-guide and means of adjustment for said stop-motion, whereby it may be operated by said guide to determine the diameter of a cop at any point during the upward movement of the guide.

The invention consists in the construction as hereinafter fully described, and pointed out in the claim.

In the drawings, which consist of two figures, Figure 1 is a perspective view, partly broken away, showing one end of a thread-winding machine having my invention adapted thereto; and Fig. 2 is a longitudinal section through the thread-tensions, showing 35 the means employed whereby the degree of tension applied to the thread may be varied according to the diameter of the cop being wound.

Referring to the drawings, *a* represents a 40 part of the frame of a thread-winding machine in which is mounted the usual driving-shaft *b*, run by a belt *c* and geared by devices not shown in the drawings with the spindle *d*, one end of which projects beyond 45 its bearing, as shown, and which receives a cop-tube on which the cops *e* are wound. Threads from suitable bobbins pass around or partly around the disk tension devices *f*, which are shown in detail in Fig. 2. These 50 threads pass through the series of slots in a guide-plate *g*, mounted upon a stem *h*, which is supported in a vertical position in a bear-

ing *i*, in which it has a sliding movement. Near the lower end of said stem a post *j* is secured thereto at right angles and projects 55 from either side thereof. On one end of said post suitable weights *k* may be hung, whereby said guide-plate *g* may be made to bear with more or less pressure on the cops as they are being wound. On the opposite end of 60 said post *j* an arm *l* extends upwardly through a slot *m* in the arbor *n*, on which the tension-disks *f* are supported. This arbor is supported in an arm *o*, extending from the frame of the machine, which is provided with a 65 transverse slot *p* at that point where the arm *l* passes through the slot *m*.

The upper end of the arm *l* has pivoted there-to a shorter arm *q*, extending downwardly through the slot *m* in the arbor *n*, and the 70 lower end of said arm *q* has a screw *r* passing therethrough, whose point rests against the arm *l*, and the latter is slotted and has a screw *s* passing through said slot and threaded into a hole in the arm *q*. By means of the 75 screw *s* the arm *q* may be swung at a greater or less angle to the arm *l*, and the screw *r* is used as a set-screw for holding it in the desired position. Thus the arm *q*, together with the upper end of the arm *l*, forms a wedge, 80 the arm *l*, as shown in Fig. 2, bearing against the arm *o*, and the arm *q* bearing against one end of the slot *m* in the arbor *n*. When the guide-plate *g* rests upon the spindle *d*, the 85 ends of the arms *q* and *l* at the point of their union will lie just within the said slot *m*, and when in this position the maximum tension will be applied to the disks *f* by means of the spring *t*.

The operation of this tension device is as 90 follows: The arbor *n* is loosely held in its support *o*—that is to say, it is free to move endwise therein. The upper ends of the arms *q* and *l* or some part thereof always occupy the slot *m*. A spring *u*, superior in tension to the 95 spring *t*, is applied to one end of the arbor *n* and constantly holds the end of the slot *m* against the inclined face of the arm *q*. Now in adjusting the tension under which the threads are to be wound onto the cop the spring *t* is 100 by a suitable nut compressed more or less until the requisite resistance to separation of the disks *f* is attained. Now as the cops increase in size the guide-plate *g* is raised and

with it the stem *h* and with the latter the arms *l* and *q* and the inclined surface of the latter forced against the end of the slot *m*, the arm *l* finding its abutment against the arm 5 o. The arbor *n* is given a longitudinal movement in its support toward the spring *t*, thus taking from the latter a certain degree of its compression or tension and proportionately permitting the more easy separation of the 10 tension-disks *f*. It is thus seen that by means of the arm *q*, whose degree of inclination may be varied by means of the screws *r* and *s*, as described, any relaxation of the normal tension as the cops *e* are built up may be effected 15 as desired.

It has been found in practice that where cops are to be wound having comparatively large diameters if the same tension is maintained in winding from the center outward 20 by the time the cop is completed the tension of the center thereof is so great as to have a tendency to not only crush the tube, but to throw said center part out of line, causing it to bulge, and it is to overcome this 25 defect that means are provided herein for decreasing gradually the tension on the thread as the cop increases in diameter. Furthermore, it is found that more or less pressure upon the cops by the guide-plate gives an 30 proved finish to the cop, and to provide for this pressure weights *k* may be hung on the post *j* on the stem of the guide-plate *g*. It has been found desirable also in practice to prevent the weight of the guide-plate and its 35 attached parts from resting upon the cop-tube at the beginning of the winding operation. Therefore to relieve the cop of the weight of said plate and its parts during the first few courses a support for said plate is provided, 40 which consists of an adjusting-screw *v*, supported in a post *w*, screwed into the frame, and the stem *h* of the guide-plate rests on the top of this screw when the cop-tube has no thread wound upon it and holds the guide- 45 plate just out of contact with said tube.

The successful operation of said winding-machine requires that the machine shall stop automatically when the desired amount of thread has been wound on the cop. The stop- 50 motion herein shown consists of a spring-actuated belt-shipper rod *x* and means for shifting it to stop and start the machine. When the belt *c*, which is engaged by a fork on the shipper-rod, is drawn onto the tight pulley, 55 (indicated by *y* in the drawings,) a spring *z* is compressed by said movement of the shipper-rod. This spring is, as shown, wound around the rod and the rod and spring enclosed in a suitable tubular support *l*. At 60 the time the belt arrives fairly onto the tight pulley *y* a spring-actuated latch *2* snaps into a notch on said shipper-rod and holds it against return movement. This latch *2* is pivoted at 3 to the frame of the machine, and its 65 opposite end is connected by an endwise-adjustable connection *4* with one end of a swing-

ing U-shaped yoke, one arm *5* of which is pivotally connected with the connection *4*. Said yoke is pivotally supported in a bearing *6*, the other arm *7* of said yoke reaching over into 70 the path of the post *j* in a position substantially parallel with the arm *5*. A spring *8* is connected with the end of the arm *5* and the frame of the machine, the function of said spring being to hold the latch *2* in engagement 75 with the shipper-rod.

It will be readily seen by the foregoing description that as the diameter of the cop increases the stem *h* will rise, carrying with it the post *j*, which will when the cop has reached 80 the desired diameter cause the arm *7* to be swung upward, whereby through the described connections with said arm the latch *2* will become disengaged from the shipper-rod and the spring on the latter will ship the 85 belt *c* from the tight to the loose pulley of the machine, arresting its motion. It is obvious, however, that owing to the fact that the guide-plate on certain sizes of cops will rise to a greater height than when smaller cops 90 are to be wound it is necessary to provide adjusting means for said stop-motion, whereby the disengagement of the latch *2* with the shipper-rod may be effected when any desired diameter of cop has been attained. In 95 other words, the stop-motion adjustment is such that it may be caused to operate at any point during the upward movement of the guide-plate *g*. This range of adjustability in the stop-motion is attained by means of the 100 endwise-adjustable connection *4*. This connection is made in two parts united by a sleeve having a right and left hand thread, into which the said two parts are screwed. By shortening said connection *4* the stop-motion 105 may be adjusted to a cop of larger diameter, and by lengthening it it may be adjusted to arrest the motion of the machine upon the attainment of a smaller diameter. To adjust the stop-motion to operate at a given point 110 during the vertical movement of the guide-plate, the latter may be raised manually to the desired height, representing the desired diameter of the cop, and the screw connection *4* be then manipulated to bring the latch *2* 115 into the detent or notch of the shipper-rod and the arm *7* to a bearing upon the post *j*. When the guide-plate reaches this point of its upward movement in the operation of winding the cop, the arm *7* will be struck by the post *j* and the latch *2* tripped, and the shipper-rod 120 will then be moved to shift the belt onto the loose pulley of the machine.

Having thus described my invention, what I claim, and desire to secure by Letters Patent 125 of the United States, is—

In a thread-winding machine, a spindle on which the thread is wound, a thread-guide bearing on the thread being wound, and adapted to be raised vertically by the building up of the thread on said spindle; a tension device consisting of a series of disks held 130

yieldingly together, an arbor on which said disks are supported, and a support for the arbor, there being a slot through the latter and said support; a wedge connected with said 5 thread-guide and entering said slots, whereby the movement of said guide vertically will move said wedge and impart endwise move-

ment to said arbor to diminish the pressure whereby said disks are held together, substantially as described.

PETER J. WESTPHAL.
